UNITED STATES PATENT OFFICE

159,304

SHOE-SHINING MACHINE

Eugene A. Thielen, Sacramento, Calif.

Application March 13, 1948, Serial No. 145,088

Term of patent 7 years

(Cl. D9—2)

To all whom it may concern:

Be it known that I, Eugene A. Thielen, a citizen of the United States, residing at 5529 Santa Barbara Avenue, county of Sacramento, State of California, have invented a new, original, and ornamental Design for a Shoe Shining Machine, of which the following is a specification, referring to the accompanying drawing, forming part thereof.

Fig. 1 is a front perspective view of a shoe shining machine showing my new design; and, Fig. 2 is a front elevational view thereof, on a reduced scale.

I claim:

The ornamental design for a shoe shining machine, as shown.

EUGENE A. THIELEN.
